UNITED STATES PATENT OFFICE.

HARRY G. GRUBBS, OF PITTSBURGH, PENNSYLVANIA.

FLUSHING CUSPIDOR.

Application filed January 13, 1923. Serial No. 612,518.

To all whom it may concern:

Be it known that I, HARRY G. GRUBBS, a citizen of the United States, residing at Pittsburgh, in the county of Allegheny and State of Pennsylvania, have invented a new and useful Improvement in a Flushing Cuspidor, of which the following is a specification.

This invention relates to a flushing cuspidor and constitutes an improvement upon the device of my prior Patent No. 678,481, dated July 16, 1901.

The device shown in the prior patent noted above is so arranged that the bowl of the cuspidor lies below the level of the floor in which the cuspidor is set. Within the bowl, adjacent the upper extremity thereof, is a perforated flushing ring connected with a water supply pipe. A drain pipe connects directly with the lower extremity of the bowl; the bowl itself is in the form of an approximately regular inverted cone; and no appreciable portion of the bowl extends above the level of the floor in which it is set.

One object of the present invention is to provide a flushing cuspidor having a bowl set permanently below the level of the floor and a removable top disposed above the floor level, but positioned on said bowl and arranged to empty thereinto.

Another object of the invention is to provide a flushing ring so arranged that it may be swung upwardly out of the bowl of the cuspidor so that, when so desired, the cuspidor may be utilized as a drain in washing the floor in which it is set.

A further object of the invention is to provide in combination with a cuspidor having an outlet arranged to permit the retention of water therein a flushing or lifting jet so arranged that in flushing the cuspidor such jet sweeps from the cuspidor water standing in the bowl thereof.

In the accompanying drawings Figure 1 is a vertical sectional view through a cuspidor forming the subject matter of the invention showing the same installed in position; Figure 2 is a fragmentary sectional view showing the cuspidor with the flushing ring thereof raised to permit use of the cuspidor as a drain; Figure 3 is an enlarged view, half plan and half horizontal section, of the flushing ring and its connections; Figure 4 is a vertical section through the

same; and Figure 5 is an enlarged vertical sectional view of the bowl of the cuspidor.

The bowl 1 of the cuspidor is, as shown in Figure 1 of the drawings, set with its upper extremity substantially level with the upper surface of a floor 2^a. This bowl is preferably formed as an integral casting and comprises a main or body portion 1^a and a discharge or outlet portion 1^b, the latter being in the general form of a gooseneck to provide a trap for the bowl. Extending circumferentially of the upper extremity of the bowl 1 is a flange 2, which has thereon vertically disposed lugs 3 for positioning the top member or cover 4 of the cuspidor. 70

Leading to the cuspidor is a water line 5, which branches at the T-connection 6 to provide a vertical flushing conduit 7 and a horizontal flushing conduit 8. Of these the branch conduit 7 leads to the flushing ring 75 9, which is pivotally mounted interiorly of the bowl 1 adjacent the upper extremity thereof.

The structure of the flushing ring 9 and the mounting therefor comprise a fitting 10, 80 which passes through an aperture 11 in the bowl 1 and is screw threaded in a coupling 12 on the supply conduit 7. The fitting 10 is preferably formed as an integral casting, and is covered to provide an interior duct or water passage 13 passing upwardly therethrough. The flushing ring 9 is not continuous, but is formed with a gap or aperture, providing extremities 14 for connection to the fitting 10. This connection is effected by 90 means of screw threaded collars 15 carried by the ring 9 to engage extension 16 of the fitting 10 leaving the ring 9 free to turn in the fitting. The ring 9 itself is provided with a plurality of spraying apertures 17, 95 which may be arranged in staggered relation on the under side of the ring or may be otherwise arranged to insure a satisfactory distribution of fine jets of water. A lug 18, which may be integral with the body of the bowl as shown, acts as a support and positive stop for the flushing ring 9 when the ring is in its operative flushing position shown in Figure 1 of the drawings. 100

In flushing the cuspidor, water flowing 105 by way of supply pipe 5 passes through the branch 7, and fitting 10, and issues from ring 9 through apertures 17 in the form of fine jets directed against the inner surface of the bowl 1 of the cuspidor. Simultane- 110

ously water flowing through supply pipe 5, and branch conduit 8, issues from flushing or lifting jet 19 in the form of a column so directed that it carries water standing in the 5 body of bowl 1 outwardly through the discharge portion 1^b thereof.

Lifting jet 19 is shown as cast integral with the bowl 1, and has an extension screw-threaded to the T-connection 6. It is cored 10 to provide a duct 20, an extended duct or chamber 21, and a constricted passage or duct 22. It should be observed that the passage 22 is directed inwardly and upwardly of the bowl 1 in such manner that 15 the column of water issuing therefrom is aimed directly at the discharge portion 1^b of the bowl, and that it does not strike any portion of the inner surface of the bowl.

In normal use of the cuspidor it is flushed 20 at regular intervals, as at the close of a working day. In such flushing the jets from the flushing ring 9 carry down from the sides of the body 1^a of the bowl any particles which may have adhered thereto, and thoroughly cleanse this portion of the bowl. Simultaneously the column of water from 25 lifting jet 19 sweeps out through discharge portion 1^b water collected in the bowl together with refuse which has collected, or 30 which is swept down into the body of the bowl.

If the cuspidor is to be used as a drain in washing the floor 2, the flushing ring is 35 swung upwardly to a position at approximately right angles to the floor, as shown in Figure 2 of the drawings. In this position the ring is clear of the bowl, so that it cannot catch and retain refuse swept or washed into the bowl from the floor 2^a. In 40 this position, further, the flushing of the cuspidor may discharge upon the floor jets of water from the apertures 17 or ring 9, to assist in the cleansing operation.

The flushing cuspidor as illustrated and 45 described above is particularly well adapted for use in office building, the work rooms of factories, and the like. In such use a number of cuspidors may desirably be connected with a single source of water supply, and the flow of water for flushing the cuspidors may also if desired be made automatic. Such arrangement, however, is not illustrated or described herein as it constitutes merely an indicated use of the subject matter 50 of the present invention.

What I claim is:

1. A flushing cuspidor comprising a bowl arranged to be disposed below the level of a floor, a stationary fitting in the wall of 60 said bowl and having a duct extending therethrough, a water supply conduit connected to said fitting, a hollow flushing ring so supported in said fitting that it may be 65 swung into a position concentric with the interior surface of said bowl or swung up-

wardly therebeyond, lugs extending vertically upward from said bowl, and a removable cover member arranged to be positioned on the bowl by said lugs.

2. A flushing cuspidor comprising a bowl, 70 a stationary fitting in the wall of said bowl and having a duct extending therethrough, a water supply conduit connected to said fitting, and a split flushing ring having open extremities rotatably mounted in said fitting, so that the ring may be swung into a position concentric with the bowl or swung upwardly therebeyond.

3. A flushing cuspidor comprising a bowl, 75 a stationary fitting in the wall of said bowl and having a duct extending therethrough, a water supply conduit connected to said fitting, a T-connection on said fitting, and a split flushing ring having open extremities and relatively straight portions adjacent 80 such extremities arranged to be rotatably secured to the connection of said fitting, so that the ring may be swung into a position concentric with the bowl or swung upwardly therebeyond.

4. A flushing cuspidor comprising a bowl arranged to lie below the level of a floor and having an outlet disposed above the bottom thereof, lugs extending vertically from the upper extremity of said bowl, a removable 90 cover member arranged to be positioned by said lugs at a point above the floor level, a jet having a constricted discharge orifice and arranged to discharge into said bowl, a column of water directed to the outlet from 95 the bowl for sweeping out water collected in the bowl, and water supply connections to said jet.

5. A flushing cuspidor comprising a bowl arranged to lie below the level of a floor and 100 having an outlet disposed above the bottom thereof, lugs extending vertically from the upper extremity of said bowl, a removable cover member arranged to be positioned by 105 said lugs at a point above floor level, a jet having a constricted discharge orifice and arranged to discharge into said bowl, a column of water directed to the outlet from 110 the bowl for sweeping out water collected in the bowl, a flushing ring pivotally 115 mounted in the bowl and arranged to direct streams downwardly along the interior surface of the bowl or to be swung upwardly therebeyond, and water supply connections to said jet and flushing ring.

6. A flushing cuspidor comprising a bowl, a rigid fitting having a duct therethrough in the wall of said bowl, a water supply conduit connected to said fitting, and a hollow 120 flushing ring in communication with the duct through said fitting and mounted directly in the fitting for rotation therein so that it may be swung into a position concentric with the interior surface of said bowl or swung upwardly therebeyond.

7. A flushing cuspidor comprising a bowl, a rigid fitting having a duct therethrough in the wall of said bowl, a water supply conduit connected to said fitting, a hollow flushing ring in communication with the duct through said fitting and mounted directly in the fitting for rotation therein so that it may be swung into a position concentric with the interior surface of said bowl or 10 swung upwardly therebeyond, and a seat integral with the interior surface of the bowl for supporting said ring in its lower position.

8. A flushing cuspidor comprising a bowl 15 arranged to lie below the level of a floor, a rigid fitting having a duct therethrough in the wall of said bowl, a water supply con-

duit connected to said fitting, a hollow flushing ring in communication with the duct through said fitting and mounted directly 20 in the fitting for rotation therein so that it may be swung into a position concentric with the interior surface of said bowl or swung upwardly therebeyond, and means on said bowl for positioning a removable cover 25 member thereon in a position above the level of the floor.

In witness whereof, I hereunto set my hand.

HARRY G. GRUBBS.
